UNITED STATES PATENT OFFICE

CLENON W. CALLAHAN, OF LYNCHBURG, VIRGINIA

CURTAIN SPREADER

Application filed May 4, 1929. Serial No. 360,509.

This invention relates to a device designed for spreading window curtains, portières or the like, and aims to provide novel means whereby a person may spread the curtains or 5 portières evenly, while standing at a point adjacent to one side of the curtains or portières.

Another object of the invention is to provide arms having curtain engaging hooks at 10 their lower ends, the hooks embracing portions of the curtains, there being provided gears for operating the arms simultaneously, the construction of the arms and gears being such that they will be invisible from a point 15 within the room.

A still further object of the invention is to provide a device of this character which may be readily and easily installed without the necessity of making alterations in the 20 window or frame construction to install the device.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the 30 scope of what is claimed, without departing from the spirit of the invention.

Referring to the drawing:

Figure 1 is an elevational view illustrating curtains equipped with a curtain spreader constructed in accordance with the invention. 35

Figure 2 is a detail view of the operating gears.

Figure 3 is a sectional view taken on line 3-3 of Figure 2.

Figure 4 is a sectional view taken on line 4-4 of Figure 1.

Referring to the drawing in detail, the reference character 5 designates curtains or portières of the hanging type, the same being 45 secured along the upper edge of a window frame or closure frame in the usual and well known manner.

The device forming the subject matter of the invention includes a supporting plate 6 50 to which the segmental gears 7 are secured,

the gears being mounted for rotary movement and so arranged with respect to each other that the teeth thereof will mesh.

The reference character 8 designates a pinion supported on the plate 6, which pinion is supplied with an arm 9 which is formed with an opening to permit one end of the flexible member 10 to be connected therewith, the flexible member being preferably in the form of a cord. This flexible member 60 operates over a pulley 11 which is secured to the window frame so that a downward pull on the flexible member 10 will swing the arm 9 in such a way as to rotate the pinion 8, which is in mesh with one of the segmental 65 gears 7, to impart movement thereto.

Secured to the pinions 7, are substantially long arms 12 which extend downwardly an appreciable distance to engage the curtains 5 at points adjacent to the lower ends of the 70 curtains. A curtain engaging hook 13 is formed at the lower end of each arm, the hooks extending laterally and embracing portions of the edges of the curtains, as clearly shown by Figure 4 of the drawing. 75

From the foregoing it will be seen that due to this construction, a pull on the flexible member 10 will cause the arms 12 to swing away from each other separating the adjacent edges of the curtain. After the curtains have been spread the flexible member 80 may be secured to hold the curtains in such position against the weight of the curtains.

It will of course be understood that the supporting plate 6 which supports the pinions and arms, is secured to the window frame adjacent to the upper portion thereof, and at a point intermediate the side edges of the frame, as shown by the drawing. 85

I claim:

1. A device for spreading curtains, comprising gears, substantially rigid members carried by the gears and engaging the curtains, and means for rotating the gears to swing the rigid members laterally to separate the curtains. 95

2. A device for spreading curtains, comprising a supporting plate, a pair of gears, the teeth of the gears meshing, arms carried by the gears and engaging the curtains to 100

swing the curtains laterally, and a pinion in mesh with one of the gears for rotating the gears to move the arms.

3. A device for spreading curtains, comprising a supporting plate, segmental gears pivotally mounted on the supporting plate and being in mesh with each other, arms connected with the segmental gears, said arms having curtain engaging hooks, a pinion mounted on the supporting plate and in mesh with one of the gears to rotate the gears, and means for operating the pinion.

4. A device for spreading curtains, comprising a supporting plate, movable members on the supporting plate, a pair of arms mounted on the movable members and engaging the curtains, a pinion for operating the movable members, an arm on the pinion, and a flexible member connected with the arm for operating the arm to rotate the pinion to move the first mentioned arms.

In testimony that I claim the foregoing as my own, I have hereto affixed my signature.

CLENON W. CALLAHAN.
